(57) **CLAIM**

The ornamental design for a cabin for pedal-driven vehicle, as shown and described.

DESCRIPTION

FIG. 1 is a front elevation view of the cabin for pedal-driven vehicle embodying the design;

FIG. 2 is a rear elevation view of the cabin;

FIG. 3 is a side elevation view of the cabin, the other side elevation view being a mirror image thereof;

FIG. 4 is a top plan view of the cabin; and,

FIG. 5 is a bottom plan view of the cabin.

The broken line showings of a pedal-driven vehicle in FIGS. 1 to 5 are for illustration purposes only and form no part of the claimed cabin.
